CLAIM

The ornamental design for a note and clip, as shown and described.

DESCRIPTION

FIG. 1 shows a perspective view of a first embodiment of a design of a note and clip.
FIG. 2 shows a right-side view of FIG. 1. A left-side view is a mirror image of the right-side view.
FIG. 3 shows another perspective view of FIG. 1.
FIG. 4 shows a front view of FIG. 1. A back view is a mirror image of the front view.

FIG. 5 shows a right-side view of FIG. 1. A left-side view is a mirror image of the right-side view.

FIG. 6 shows a back view of FIG. 1. A front view is a mirror image of the back view.

FIG. 7 shows a top view of FIG. 1.

FIG. 8 shows a bottom view of FIG. 1.

FIG. 9 shows a perspective view of a second embodiment of a design of a note and clip.

FIG. 10 shows a right-side view of FIG. 9. A left-side view is a mirror image of the right-side view.

FIG. 11 shows another perspective view of FIG. 9.

FIG. 12 shows a front view of FIG. 9. A back view is a mirror image of the front view.

FIG. 13 shows a right-side view of FIG. 9. A left-side view is a mirror image of this right-side view.

FIG. 14 shows a back view of FIG. 9. A front view is a mirror image of the back view.

FIG. 15 shows a top view of FIG. 9.

FIG. 16 shows a bottom view of FIG. 9.

FIG. 17 shows a perspective view of a third embodiment of a design of a note and clip.

FIG. 18 shows a right-side view of FIG. 17. A left-side view is a mirror image of the right-side view.

FIG. 19 shows another perspective view of FIG. 17.

FIG. 20 shows a front view of FIG. 17. A back view of this embodiment is a mirror image of the front view.

FIG. 21 shows a right-side view of FIG. 17. A left-side view of this embodiment is a mirror image of the right-side view.

FIG. 22 shows a back view of FIG. 17. A front view of this embodiment is a mirror image of the back view.

FIG. 23 shows a top view of FIG. 17.

FIG. 24 shows a bottom view of FIG. 17.

FIG. 25 shows a perspective view of a fourth embodiment of a design of a note and clip.

FIG. 26 shows a right-side view of FIG. 25. A left-side view of this embodiment is a mirror image of the right-side view.

FIG. 27 shows another perspective view of FIG. 25.

FIG. 28 shows a front view of FIG. 25. A back view of this embodiment is a mirror image of the front view.

FIG. 29 shows a right-side view of FIG. 25. A left-side view of this embodiment is a mirror image of the right-side view.

FIG. 30 shows a front view of FIG. 25. A back view of this embodiment is a mirror image of the front view.

FIG. 31 shows a top view of FIG. 25.

FIG. 32 shows a bottom view of FIG. 25.

FIG. 33 shows a perspective view of a fifth embodiment of a design of a note and clip.

FIG. 34 shows a right-side view of FIG. 33. A left-side view of this embodiment is a mirror image of the right-side view.

FIG. 35 shows another perspective view of FIG. 33.

FIG. 36 shows a front view of FIG. 33. A back view of this embodiment is a mirror image of the front view.

FIG. 37 shows a right-side view of FIG. 33. A left-side view of this embodiment is a mirror image of the right-side view.

FIG. 38 shows a front view of FIG. 33. A back view of this embodiment is a mirror image of the front view.

FIG. 39 shows a top view of FIG. 33.

FIG. 40 shows a bottom view of FIG. 33.

FIG. 41 shows a perspective view of a sixth embodiment of a design of a note and clip.

FIG. 42 shows a right-side view of FIG. 41. A left-side view of this embodiment is a mirror image of the right-side view.

FIG. 43 shows another perspective view of FIG. 41.

FIG. 44 shows a front view of FIG. 41. A back view of this embodiment is a mirror image of the front view.

FIG. 45 shows a right-side view of FIG. 41. A left-side view of this embodiment is a mirror image of the right-side view. FIG. 46 shows a front view of FIG. 41. A back view of this embodiment is a mirror image of the front view. FIG. 47 shows a top view of FIG. 41; and, FIG. 48 shows a bottom view of FIG. 41.

The surfaces of the note are entirely unclaimed except for the edge lines that are shown as solid lines. The broken-line features in the figures are for illustrative purposes only and form no part of the claimed design.
